US00D449909B1

(12) **United States Design Patent**
Randolph et al.

(10) Patent No.: **US D449,909 S**
(45) Date of Patent: ** Oct. 30, 2001

(54) **CLEANING DEVICE**

(75) Inventors: **Ross Steven Randolph**, Rockaway;
Francis X. Manganiello, Pompton
Plains; **Nicholas E. Barker**, Saddle
River, all of NJ (US)

(73) Assignee: **Playtex Products, Inc.**, Westport, CT
(US)

(**) Term: **14 Years**

(21) Appl. No.: **29/113,313**

(22) Filed: **Nov. 1, 1999**

(51) LOC (7) Cl. **04-01**

(52) U.S. Cl. **D32/40**; D4/138

(58) Field of Search D4/128, 131, 137,
D4/138; 15/143.1, 145, 164, 165, 206,
207, 211, 212, 229.13, 244.1; 16/110.1,

(57) **CLAIM**

The ornamental design for a cleaning device, as shown and described.

DESCRIPTION

FIG. 1 is a perspective view of a cleaning device showing our new design, with a cleaning head, which is oriented on the front adapter portion, being for illustrative purposes only and forming no part of the claimed design;

FIG. 2 is a top view of the cleaning device of FIG. 1;
FIG. 3 is bottom view of the cleaning device of FIG. 1;
FIG. 4 is a side elevation view of the cleaning device of FIG. 1;

FIG. 5 is a front view of the cleaning device of FIG. 1;
FIG. 6 is a rear view of the cleaning device of FIG. 1;
FIG. 7 is a perspective view of the cleaning device showing the front adapter removed for clarity of illustration only and with a cleaning head being shown in broken lines for illustrative purposes and forming no part of the claimed design;

FIG. 8 is a top view of the cleaning device of FIG. 7;
FIG. 9 is bottom view of the cleaning device of FIG. 7;
FIG. 10 is a left side elevation view of the cleaning device of FIG. 7;

FIG. 11 is a right side elevation view of the cleaning device of FIG. 7;

FIG. 12 is a front view of the cleaning device of FIG. 7; and,
FIG. 13 is a rear view of the cleaning device of FIG. 7.
